US0D1096633S

(12) **United States Design Patent** (10) Patent No.: **US D1,096,633 S**
(45) Date of Patent: ** Oct. 7, 2025

(54) **TRIANGULAR ELEMENT OF A BATTERY ENCLOSURE**

(71) Applicant: **SABIC Global Technologies B.V.**,
Bergen op Zoom (NL)

(72) Inventor: **Fred Chang**, Wixom, MI (US)

(73) Assignee: **SABIC Global Technologies B.V.**,
Bergen op Zoom (NL)

(**) Term: **15 Years**

(21) Appl. No.: **35/520,398**

(22) Filed: **Dec. 14, 2023**

(80) **Hague Agreement Data**

Int. Filing Date: **Dec. 14, 2023**

Int. Reg. No.: **DM/235760**

Int. Reg. Date: **Dec. 14, 2023**

Int. Reg. Pub. Date: **Mar. 22, 2024**

(57) **CLAIM**

The ornamental design for a triangular element of a battery enclosure as shown and described.

DESCRIPTION

FIG. 3.1 shows a top perspective view of a triangular element of a battery enclosure;

FIG. 3.2 shows a top view thereof;

FIG. 3.3 shows a bottom view thereof;

FIG. 3.4 shows a side view thereof; and

FIG. 3.5 shows another side view thereof.

Broken lines in the drawings represent portions of the triangular element of a battery enclosure that form no part of the claimed design.
